UNITED STATES PATENT OFFICE.

FREDERICK R. KALDENBERG, OF NEW YORK, N. Y.

HANDLE FOR CUTLERY.

SPECIFICATION forming part of Letters Patent No. 396,091, dated January 15, 1889.

Application filed December 9, 1887. Serial No. 257,472. (No model.)

To all whom it may concern:

Be it known that I, FREDERICK R. KALDENBERG, a citizen of the United States, residing at New York, in the county and State of New 5 York, have invented certain new and useful Improvements in Handles for Cutlery, of which the following is a full, clear, and exact specification.

My invention has for its object the construction of a simple and durable handle for cutlery which is susceptible of a varied degree of ornamentation by the union of materials which differ essentially in color and general appearance; and to accomplish this I form 15 the handle of several sections mounted on a core or shank provided with a flange at one end, and having a screw-threaded extremity fitting into a threaded end section, so that the several sections are firmly clamped together 20 to form a solid handle.

In the accompanying drawings, which fully illustrate my improvement, Figure 1 is a side elevation of a knife-handle made according to my invention; and Fig. 2 is a sectional view 25 of the same, with the shank shown partly in elevation.

Let *a* represent the core or shank of the handle, on which the several sections which compose the body of the handle are mounted. 30 This is made tubular its entire length, or provided with a suitable recess, *b*, extending partly through the same, for the reception of the tang of the knife-blade, which is secured therein by means of molten lead or other material in the usual manner. On the inner end 35 of the shank is formed a flange, *c*, which may be either soldered, screwed, or wedged on its

extremity to form a bearing-piece for the upper section, *g*, and, in connection with the screw, constitute the clamping device. The 40 opposite end of the shank is provided with a screw-thread, *d*, and is made to screw into a correspondingly-threaded socket formed in the outer end section, *f*, of the handle.

The body of the handle is composed of the 45 two end sections, *f* and *g*, the central section, *h*, and the two intermediate sections, *i* and *j*. These sections, with the exception of the lower one, are provided with a central perforation to receive the shank *a*. The sections 50 are made to differ essentially in color and external configuration, so that a highly-ornamental effect can be given to the handle. After the sections are mounted on the shank, the end section is screwed on, which serves to 55 clamp the intervening sections firmly together. On the under side of the flange *c* is provided one or more pins or screws, *b'*, which fit into recesses in the upper section, *g*, to prevent the shank and flange from turning when 60 under strain.

What I claim as new, and desire to secure by Letters Patent, is—

A handle for cutlery, consisting of a tubular shank or core provided with a flange at one 65 end, and having a screw-threaded extremity fitting a threaded socket in an end section, and intermediate sections mounted on said shank to form a solid handle, as set forth.

FREDERICK R. KALDENBERG.
